UNITED STATES PATENT OFFICE.

THOMAS HARDING, OF NEWARK, NEW JERSEY, ASSIGNOR TO J. L. SOMMER MANUFACTURING CO., A CORPORATION OF NEW JERSEY.

GARMENT-HANGER.

1,282,076.

Specification of Letters Patent. Patented Oct. 22, 1918.

Application filed August 30, 1915. Serial No. 47,924.

To all whom it may concern:

Be it known that I, THOMAS HARDING, a citizen of the United States, and a resident of Newark, in the county of Essex and State 5 of New Jersey, have invented certain new and useful Improvements in Garment-Hangers, of which the following is a specification.

The objects of this invention are to provide an improved garment hanger for hanging up an entire suit or both coat and trousers; to enable the same to fold compactly when not in use, and not become entangled or difficult to open; to properly balance the hanger when loaded; to secure simplicity of construction and operation, and to obtain other advantages and results as may be brought out in the following description.

Referring to the accompanying drawing, 20 in which like numerals of reference indicate the same parts throughout the several views,

Figure 1 is a side elevation of my improved garment hanger in open position;

Fig. 2 is a similar elevation showing the garment hanger in closed or folded position;

Fig. 3 is an elevation taken on the opposite side from that shown in Figs. 1 and 2 and showing the garment hanger partially 30 folded, and

Fig. 4 is an edge view of the garment hanger folded.

In the specific embodiment of the invention illustrated in said drawing, the reference numeral 1 indicates an elongated supporting member preferably bent and stamped from wire and providing a hook 2 at its upper end by which it may be hung up and being flattened for its lower end portion, as 40 at 3, in substantially the same plane with the hook. At its lower end, said flattened portion 3 is perforated and receives a rivet or other pivoting means 4 by means of which a pair of similar arms 6, 6 are pivoted 45 to the flattened portion 3 of the supporting member flatwise thereof, preferably both upon the same side, and adapted in open position to extend transversely away from said member in substantial alinement with 50 each other. To limit their opening to such a position, said arms are shown as each having a stop 7 adapted to engage the side edge of the flattened portion of the supporting member, when opened, said stop being preferably stamped up from the arm itself.

The outer or free ends of the arms are shown as turned back and resiliently engaging the arms flatwise, as at 8, and furthermore the extremities of the turned-back portions preferably curve outwardly away from 60 the body of the arm, as at 9, whereby trousers or the like may be readily wedged therebetween.

Above the pivotal support for the trousers arms 6, 6, another perforation is made in 65 the supporting member 1, preferably at the upper end of the flattened portions, and a rivet 10 or the like hingedly carries a pair of arms 12, 12 pivoted at their inner ends upon said rivet, preferably on opposite sides 70 of the supporting member and adapted to curve downward therefrom when extended. Suitable stops are provided for limiting downward swing of the arms, said stops being here shown as formed by flattening the 75 arms around the pivot so that shoulders 13 are formed adapted to engage the edge of the supporting member 1. As shown, the pivoted ends of the arms are each bent edgewise of themselves and parallel to the 80 flattened portion 3 of the supporting member, whereby the shoulders 13 are positioned farther from the pivot 10 and eccentric with respect thereto so as to obtain greater purchase. 85

Above the coat arms, the supporting member curves or bows away from the same in a plane transverse to the arms, thereby affording proper accommodation for the collar of a coat hung upon the hanger. Said 90 curved portion or bow is designated herein by reference numeral 14, and is preferably semi-circular, and the hook 2 at the top thereof is thereby in substantially the same plane with the lower flattened portion 3. 95

By an inspection of Figs. 2, 3 and 4 it will be noted that the coat arms 12, 12 of the hanger may be swung upward substantially parallel with and adjacent to the supporting member 1, overlapping each 100 other somewhat so as to occupy minimum space. The trousers arms 6, 6 of the hanger also swing upwardly substantially side by side with the supporting member 1, so that the whole folds compactly into a convenient 105 size and shape. Obviously when it is desired to use the garment hanger the coat and trousers arms may be quickly and easily turned down into their operative or extended position as shown in Fig. 1. 110

It will be further noted that when folded, the arms of the trousers hanger overlie the arms of the coat hanger, and the arms of the coat hanger may be swung down into their operative or extended position while the arms of the trousers hanger are folded up, and this is obtained by pivoting the arms as shown. That is to say, the upper or coat arms fold together at the opposite side 10 of the suspending hook 2 from the lateral bow 14, while the lower or trousers arms fold against said bow at the same side of the coat arms when folded as the suspending hook. To accomplish this I have shown the 15 arms of the coat hanger are upon opposite sides of the stem whereas the arms of the trousers hanger are upon only one side of the stem, one overlying the other where pivoted. The arm 6, included between the other 20 or overlying arm 6 and the stem, extends laterally in the same general direction as the arm of the coat hanger which is pivoted on the opposite side of the stem from the trouser hanger, whereas the outer or overlying 25 arm 6 of the trousers hanger extends in the same general direction as the arm of the coat hanger on the same side of the stem therewith. In this manner the arms of the trousers hanger are prevented from interfering 30 with the arms of the coat hanger. Furthermore the coat hanger preferably curves outwardly downward from its support upon the stem and the trousers hanger is made short enough to be included within the curvature of said coat hanger, thus obtaining an attractive and compact arrangement 35 of parts in operative position.

I have shown the coat arms of wire and the trousers arms of sheet metal, but obviously various modifications and changes 40 may be made in the manufacture of my improved garment hangers without departing from the spirit and scope of the invention, and I do not wish to be understood as limiting myself except as required by the following claim, when construed in the light of 45 the prior art.

Having thus described the invention, what I claim is:—

In a garment hanger, the combination 50 of a supporting member having suspending means at its upper end and a lateral bow intermediate its ends, said bow and suspending means being in planes substantially at right angles to each other, a pair of arms 55 pivoted to opposite sides of said supporting member below said lateral bow to swing transverse thereto and fold together at the opposite side of the suspending means from said bow, and a second pair of arms below 60 the first-mentioned arms pivoted both to the same side of the supporting member as the bow to swing in a plane transverse to said bow and fold thereagainst at the same side of the first-mentioned arms when folded as 65 the suspending means, the arm of the second pair which is next the supporting member being adapted to swing in the same direction as the arm of the first-mentioned pair which is on the opposite side of the supporting member, whereby the other two arms are spaced although on the same side of the 70 supporting member.

THOMAS HARDING.
